MANUFACTURE OF BARBED WIRE

Hans Thiemer, Cologne-Mulheim, and Peter Hillesheim, Cologne-Holweide, Germany, assignors to Felten & Guilleaume Earlswerk Eisen und Stahl Actiengesellschaft, Cologne-Mulheim, Germany

Application September 13, 1938, Serial No. 229,744
In Germany September 17, 1937

4 Claims. (Cl. 140—60)

In the usual mode of manufacture of barbed wire the barb carrier which may be a single wire or a strand, is, by alternately driving and braking the draw carriage of the barbed wire machine, drawn intermittently through the barbed wire machine, as the bunches of barbs can only be inserted, when the carrier wire or the carrier strand is stationary. This intermittent motion stresses the machine very heavily and results in considerable wear of the individual parts of the machine.

The invention avoids these disadvantages. According to the invention, in the manufacture of barbed wire the wire or wires forming the barb carrier are not drawn intermittently through the machine as heretofore, but are fed into the machine at an always constant speed and are only momentarily arrested in front of the barb twister at equal intervals of time for the insertion of the bunches of barbs. During the insertion of the bunches of barbs a loop will thus each time be formed in the barb carrier, owing to the wire or wires forming the latter being fed forward, which loop is however used up again, as soon as the insertion of the bunch of barbs has been completed.

The machine according to the invention differs from the usual barbed wire machines in this, that on the feed side one or more pairs of fluted rollers or similar devices for the uniform forward feed of the wires of the barb carrier are provided and that in front of the barb twister there is disposed an arresting device for holding the wire or wires of the barb carrier at the moment of insertion of the bunches of barbs. The barb twister consisting of the devices for feeding, twisting and cutting off the barb material is already known, and does not form part of the invention.

The drawings show in Fig. 1 a barbed wire machine according to the invention in elevation. Fig. 2 is a section on the line A—A in Fig. 1. Fig. 3 shows a part of the device for feeding the barb material as seen from the lefthand side of Fig. 1. Fig. 4 shows the device for winding the barb material in section as seen from above. Fig. 5 shows the holding device for the wires of the barb carrier in longitudinal section. Fig. 6 is a cross-section on the line B—B in Fig. 5. Fig. 7 shows in longitudinal section a modification of the holding device. Fig. 8 is a cross-section on the line C—C in Fig. 7. Further details and the mode of operation of the machine are described below.

On the base 1 of the machine (see Figs. 1 and 2) is mounted the main driving shaft 2 which is driven by means of pulley 3 and belt 4. The shaft 2 drives through the wheels 5 and 6, the auxiliary shaft 7, which itself drives through toothed wheels

of which one pair are indicated by 8 and 9 in Fig. 2, the driving shafts 10 and 11 of the pairs of fluted rollers 12 and 13 with uniform speed. The individual rollers of each pair 12 and 13 are coupled together by the toothed wheels 14. By means of the pairs of rollers 12 and 13 and the grooves 15 (Fig. 2) on the rollers, the wires 18 and 19 from the supply reels 16 and 17 are gripped and fed with uniform speed into the machine.

The holding device 20 for holding the wires 18 and 19 while the barbs are being applied is described below. It is driven from the auxiliary shaft 21 which is coupled through the toothed wheels 22 and 23 with the shaft 2.

The auxiliary shaft 26 is coupled with the shaft 2 through the toothed wheels 24 and 25. On the auxiliary shaft 26 is secured the crank disc 27 which by means of the crank 28 actuates the swinging lever 29 which by means of the detent 30 moves the wheel 31 with the shaft 32 a certain distance at each revolution of the shaft 26. The shaft 32 which in this way is driven intermittently drives the device for feeding the barb material 33 and 34. This device consists of the reels 35 and 36 on which the barb material 33 and 34 is wound. The pairs of fluted rollers 37 and 38 which feed the barb material and the guiding blocks 39 and 40 introduce the barb material between the wires 18 and 19 before they are twisted together. The upper roller of the pair 37 (Fig. 3) which is secured on the shaft 32 is coupled with the lower roller through the toothed wheel 41. The guiding blocks 39, 40 (Figs. 2 and 3) have curved passages 42 through which the barb material 33 and 34 is introduced between the wires 18 and 19. While the pair of rollers 37 is driven directly by the shaft 32, the pair 38 of which the upper roller is mounted on the shaft 43 is coupled with the shaft 32 by means of the shaft 43, the toothed wheels 44 and 45, the auxiliary shaft 46 and the toothed wheels 47 and 48.

The device for twisting the barbs (Figs. 1, 2 and 4) consists of the hollow cylinder 50 mounted in the bearing block 49 which at its rear end is provided with twisting members 51. In the hollow space of the cylinder 50 (Fig. 4) projects the stationary tongue 52 which holds the wires 18 and 19 of the barb carrier apart until shortly before they reach the twisting place. On the cylinder 50 is mounted at its front end the toothed ring 53. For driving the barb twisting device there is mounted on the auxiliary shaft 26 the crank disc 54 which actuates the swinging lever 56 by means of the crank 55. The toothed segment 57 of the swinging lever 56 engages with the ring 53 of the

cylinder 50. The arrangement is such that the cylinder 50 carrying the members 51 is actuated at the instant when the barb material 33 and 34 is fed by the roller pairs 37 and 38 through the 5 bores 42 of the guiding blocks 39 and 40 and between the wires 18 and 19 of the barb carrier so far that it can be gripped by the members 51 of the cylinder 50.

The device for cutting off the barb material 10 (Figs. 1 and 2) consist of the rotatably mounted cutter carrier 58 with the cutters 59 and 60 and the curved lever arm 61. For driving the cutting device an auxiliary shaft 62 is provided which is coupled with the shaft 2 through toothed wheels 15 63 and 64. On the other end of the shaft 62 is secured the crank disc 65 which actuates the lever 61 of the cutting device by means of the crank 66. The cutters 59 and 60 when moved upwards slide with their cutting edges on the 20 surfaces 67 and 68 of the guiding blocks 39 and 40 and thereby cut off the barb material coming out of the passages 42 at the surfaces 67 and 68. The arrangement is made such that the cutters 59 and 60 are moved upwards on the surfaces 25 67 and 68 of the guiding blocks 39 and 40 each time the barb material is wound around the wires 18 and 19 of the barb carrier by means of the carriers 51 of the twisting device.

The winding drum 69 for the finished barb 30 wire is mounted in the rotatable frame 70. This frame is coupled with the shaft 2 through the toothed wheels 71 and 72 and when rotating effects the twisting of the wires 18 and 19 together. The winding drum 69 is driven by means of the 35 belt 73. This drives by means of the pulley 74 the auxiliary shaft 75 mounted in the hollow shaft of the wheel 72, which shaft 75 is coupled with the drum 69 by means of the toothed wheels 76 and 77. The holding device 20 for holding the 40 wires 18 and 19 while the barbs are being inserted (Figs. 5 and 6) consists of the bearing block 78, the slideable element 79, the bridge 80 and the balls 81 and 82. The bearing block 78 has a cylindrical bore 83 which at the front end 45 is flared conically at 84. The slideable element 79 is made conical at the front and cylindrical at the rear so that it fits into the hollow space 83, 84 of the bearing block 78. In the axial bore 85 of the element 79 is secured the bridge 80 which 50 has grooves 86, 87 at both its flat sides. By means of the bridge 80 two separate passages are formed in the axial bore 85 of the element 79 through which the wires 18 and 19 are drawn, being guided in the grooves 86 and 87. The conical part of 55 the element 79 is provided with radial bores 88 and 89 along a diameter at right angles to the bridge 80 in which balls 81 and 82 are placed. The balls 81 and 82 are of such size that when 60 the wires 18 and 19 are drawn in, the balls project somewhat beyond the conical part of the element 79. At the front end which projects out of the block 78 the element 79 has an annular groove 90. In this (see Fig. 2) engages the guide fork 91 of the lever 92 which is actuated under 65 the action of the spring 93 by the cam disc 94 on the auxiliary shaft 21, and with it the cam disc 94 make a complete revolution from the beginning of the insertion of a bunch of barbs until the beginning of the insertion of the next bunch. 70 The extent of the thickening 95 of the cam disc 94 corresponds to the time between two successive barb inserting operations. Each time a bunch of barbs is inserted the spring 93 presses the element 79 into the conical bore 84 of the bearing 75 block 78 whereby the balls 81 and 82 in the radial

bores 88 and 89 of the element 79 are pressed inwardly and clamp the wires 18 and 19 sliding in the grooves 86, 87 of the bridge 80. When a bunch of barbs has been inserted the disc 94 has rotated until its thickened part comes into engagement with the lever 92. This lever with its guide fork 91 then draws the element 79 against the action of the spring 93 so far that the balls 81 and 82 are relieved from pressure and the wires 18, 19 are released. 10

For equalising the intermittent movement which the wires 18 and 19 of the barb carrier experience in the twisting device, the barbed wire before reaching the winding device 69, 70 is guided over the tensioning roller 99 arranged between the two guiding rollers 96 and 97 and acted upon by the spring 98. In this way a steady winding up of the finished barbed wire is made possible. 15

For the manufacture of single wire barbed wire, 20 that is a barbed wire with only one wire for the barb carrier, the element 79 of the holding device (Figs. 7 and 8) has a correspondingly smaller axial bore 85 without a bridge through which the wire 18 is drawn. Correspondingly the slideable 25 element 79 has only one radial bore 88 with a ball 81 for holding the wire 18, while the barbs are being applied.

Apart from the protection afforded to the individual parts of the machine, the method according to the invention has the further advantage, that the distances between the barbs will be exactly equal to one another, as, through the uniform forward feed of the wires of the barb carrier, portions of wire of exactly the same length 35 will be delivered between the moments of insertion of successive bunches of barbs. For the same reason a far more reliable measuring and supervision of the manufactured lengths of barbed wire is possible, than is the case in the known 40 methods and machines for the manufacture of barbed wire. 45

What we claim is:

1. A machine for producing barbed wire having a barb carrier consisting of a single wire, comprising means for feeding the said wire continuously and at a uniform speed into the machine, a barb twisting device and, disposed before the barb twisting device, a bearing block having an axial bore which flares conically at one end, an element with an axial bore, which is slideable in the bore of the bearing block, has a conical portion of the same conicity and a radial bore in the conical portion, a lever engaging said slideable element for pressing the said element into the said bearing block at equal intervals of time and a ball disposed in the said radial bore, which, when the wire is in the axial bore of the said element, projects beyond the conical surface of the element, for clamping the wire each time the element is pressed into the bearing block. 50

2. A machine for producing barbed wire having a barb carrier consisting of two wires, comprising means for feeding the said wires continuously and at a uniform speed into the machine, a barb twisting device and, disposed before the barb twisting device, a bearing block having an axial bore which flares conically at one end, an element with an axial bore, which is slideable in the bore of the bearing block, has a conical portion of the same conicity and two radial bores in the conical portion, a bar disposed in the axial bore of the said element and having two grooves, one on each side, for guiding the two wires of the barb carrier, a lever engaging said slideable ele- 75

ment for pressing the said element into the said bearing block at equal intervals of time and two balls, each disposed in one of the said radial bores of the element, which, when the two wires of the 5 barb carrier are in the axial bore of the element, project beyond the conical surface thereof for clamping the two wires of the barb carrier each time the element is pressed into the bearing block.

3. In a machine for producing barbed wire, in 10 combination, means for feeding the wires forming the barb carrier continuously and at a uniform speed into the machine, an intermittently operated barb twisting device for applying the barbs successively to the said wires, and, arranged in 15 front of the barb twisting device, intermittently actuated holding means for gripping said wires and holding them fast whenever the barb twisting device is operated for applying the barbs to the wires.

20 4. In a machine for producing barbed wire, in

combination, means for feeding the wires forming the barb carrier continuously and at a uniform speed into the machine, a barb twisting device, and, arranged in front of the barb twisting device, a bearing block having an axial bore 5 which flares conically at one end, an element having axial guides for the wires forming the barb carrier and which is slidable in the bore of the bearing block and has a conical portion of the same conicity and radial bores in the 10 conical portion, a lever engaging said slidable element for pressing the element into the bearing block at equal intervals of time, and balls in the radial bores of the element, which when the wires of the barb carrier are in the axial guides of the 15 element, project beyond the conical surface thereof for clamping the wires of the barb carrier each time the element is pressed into the bearing block.

HANS THIEMER.
PETER HILLESHEIM. 20
